(57) **CLAIM**

(**) Term: **14 Years**

The ornamental design for an side panel for ink cartridge for ink jet printer, as shown and described.

(21) Appl. No.: **29/113,678**

DESCRIPTION

(22) Filed: **Nov. 10, 1999**

FIG. 1 is a top plan view of a side panel for ink cartridge for ink jet printer showing our new design;

(30) **Foreign Application Priority Data**

FIG. 2 is a bottom plan view thereof;

May 14, 1999 (JP) 11-12707

FIG. 3 is a left side view thereof;

(51) LOC (7) Cl. **18-02**

FIG. 4 is a right side view thereof;

(52) U.S. Cl. **D18/56**; 347/86

FIG. 5 is a perspective view as viewed from front and

(58) **Field of Search** D18/56; 347/86-87

FIG. 6 is a perspective view as viewed from rear and top

(56) **References Cited**

direction thereof.
